UNITED STATES PATENT OFFICE.

PHILIP P. NUNGESSER, OF CLEVELAND, OHIO, ASSIGNOR, BY MESNE ASSIGNMENTS, TO NATIONAL CARBON COMPANY, INC., A CORPORATION OF NEW YORK.

MACHINE FOR SOLDERING BINDING-POSTS.

1,286,886.

Specification of Letters Patent.

Patented Dec. 3, 1918.

Application filed August 31, 1914. Serial No. 859,826.

To all whom it may concern:

Be it known that I, PHILIP P. NUNGESSER, a citizen of the United States, residing at Cleveland, in the county of Cuyahoga and State of Ohio, have invented certain new and useful Improvements in Machines for Soldering Binding-Posts, of which the following is a specification.

This invention has reference to a machine for soldering binding posts on dry-battery cans, all substantially as shown and described and particularly pointed out in the claim.

In the accompanying drawings, Figure 1 is a front elevation of the machine and Fig. 2 is a sectional elevation at right angles to Fig. 1.

Fig. 3, Sheet 2, is a plan view on a line corresponding substantially to 3—3, Fig. 5. Fig. 4 is a plan view of the machine with the flux receptacle removed. Fig. 5 is a side view of the machine. Fig. 6 is a modification of the heating means for the plunger. Figs. 7 and 8 are enlarged views of details as hereinafter fully described.

The machine as herein shown embodies improved means for soldering binding posts on dry battery cans or jars, as above indicated, and the improvement greatly simplifies and cheapens the operation.

The machine is designed to be operated by means of a treadle T, so that the operator has the machine under individual control and can govern the speed according to his own ability or experience in handling the work. Otherwise, the work he does is manual and only in connection with the can C, which he is required to place into and take from the machine and while the binding post 2 is temporarily engaged thereon. The base of said post is split or bi-furcated and adapted to straddle and clamp on the edge of the can with more or less firmness. A suitable trough shaped support or holder h serves as a rest for said can, and is adjustable as to elevation on the screw threaded post which carries the same from the base B of the machine. Otherwise all the work is automatic and practically instantaneous from one stop to the other.

Now, assuming that a can has been put in place on holder h, the threaded end of the post 2 is inserted into or through a guide or centering hole in a cross bar 3, Figs. 2 and 5, which bar is fixed on the permanent upright

posts or rods 4. Thus the said bar with its hole for said screw or post fixes the position of the post in respect to the soldering instrumentalities as well as serving as a guide to the operator.

The next step is to supply the necessary flux to the post to facilitate soldering and the receptacle R serves as a source of supply for this fluid. The tube or pipe 5 delivers the flux in sufficiently minimized quantity to meet the need of a single soldering operation, say a drop or less, and the said pipe is supported in a sleeve 6 from or by an arm a at its upper end and is adapted to have a limited rotation axially in said sleeve subject to a retracting spiral spring s at its top to pull it back so that as said tube is rotated forward at its bent lower end by engagement of the trigger 7 with the finger f thereon, the said spring will rotate the tube back to normal position the instant the flux has been delivered by said tube or pipe on the post.

In this operation the asbestos wick w on the lower end or tip of said pipe 5 is moved across the base of the binding post by the trigger 7 striking the finger f on said pipe and giving the wick a wiping action on the post. But the instant that this occurs the finger f is released from the trigger and reTRACTING SPRING S SWINGS THE SAID PIPE OR TIP OF THE PIPE TO ONE SIDE OF THE POST 2 OUT OF THE WAY. A YOKE y HAS FINGERS BETWEEN WHICH THE TRIGGER 7 HAS A LIMITED NEEDED PLAY.

The next step is the delivery of the solder immediately upon the flux covered portion of said post. This is done by feeding the solder strand or wire 8 forward from the drum D on which it is wound by means of a pair of rolls 9 and 9' mounted on different shafts 10 and 11 and having pinion connection 12, in this instance, so as to rotate said rolls in unison and afford a positive feed. The quantity of solder employed at any one time is comparatively small, say about the size of a grain of wheat, or less, according to the work to be done. The said rolls and shafts are accordingly rotated the desired distance each time by means of a ratchet wheel r on shaft 10 and a spring pressed pawl 13, Fig. 5, on an arm 14 having a head rotatably fixed on the end of shaft 10 outside of said ratchet wheel and adapted to be rocked within limits at its otherwise free

or outer end by means of the rod extension 16 thereon and the link 17 which is secured at its other end to the sliding or reciprocating frame 20.

5 The said frame, Fig. 1 is shown as consisting of two cross bars spaced apart and alike slidable on the standards 4, and said bars are connected by rods at their ends, thus making a rigid frame of the said parts

10 which has a limited up and down movement primarily derived from or through the treadle T and the rod 22 which connects said treadle directly with the said frame, Fig. 2.

15 One of the functions of the said reciprocating frame is to actuate the soldering plunger P, which is adjustably fixed in said frame at its side and center and in direct alinement with the projecting tip or end of the solder strand 8 as the same has been

20 fed forward by the rolls 9 and 9' through its guide tube 15, as seen in Figs. 2 and 5. The lower soldering end of the plunger is shaped to conform more or less closely to the contour of the base of the binding post

25 2 to which the solder really is applied by said plunger, and it is planned that the plunger shall descend directly at the end of said guide tube or pipe 15 and not only sever the solder with a shear cut but also

30 melt the same at the same time and cause it to flow into soldering relation.

Means are therefore provided for heating the plunger, and I may employ a blow pipe or medium m as seen in Fig. 1, which maintains a heating flame of sufficient intensity against the exposed end of the plunger, or I may employ an electric heater E as shown in Fig. 6.

35 40 The said plunger having done its work through the descent of frame 20 actuated by treadle T, it is instantly raised again by the lift spring S mounted on said frame and engaged at its upper end with the cross bar 25 which connects the upper end of the standards 4 and constitutes a portion of the main frame of the machine.

45 The distance of travel of the plunger is comparatively short, as will be seen in Fig. 50 1 by its elevation above the solder tip 8, and its down movement is controlled exclusively by treadle T and its up and return movement by the spring S, which are in quick succession so that both are accomplished in a moment. The soldered can is then ready to be removed and replaced by another, and so on with great speed by an expert workman.

55 60 The working elevation of the flux tube or pipe 5 is fixed by adjustment to meet its position in respect to the post 2, and the trigger 7 mounted pivotally in the frame 20

rotates said pipe just far enough to carry its delivery over the said post when the said finger flips by said trigger and the spring s 65 rotates the pipe back to starting position out of the way of the descending plunger which comes on to the spot the instant that said pipe is turned aside.

The feed rolls 9 and 9' for the solder 70 strand and the parts associated therewith are supported from the base B by a standard 30 and bracket 31 thereon, Fig. 8.

75 The flux supply vessel R is shown as supported by arm 32 from the top of the main frame, and the flux drops visibly from said vessel into the funnel shaped end of the pipe 5 and the flow is regulated by means of a valve.

80 The contact of the plunger P with the binding post 2 on can C is more of the nature of a touch than anything else, since the sole object thereof is to cover and melt the solder in a flowing state upon said post and which spreads sufficiently to engage the 85 post with the can. The extremity of the plunger usually is kept at substantially a red heat so that its work is instantaneous and it no sooner reaches the limit of its stroke than it is withdrawn. Naturally, 90 there is a tendency in the guide tube 15 to heat from the plunger, but precaution can be taken not to have said parts contact and thus minimize the heating tendency in said tube. Otherwise the further precaution can 95 be employed of swinging the said tube laterally a short distance the instant the solder is severed so as to minimize the impartation of heat from the plunger. A slight movement will do and this is effected by the sup- 100 port 35 pivoted at 34, Fig. 2 for the end of the tube and the inclined arm 36, Fig. 1, bearing against the said tube and pressing it aside. The end of the said arm is bent laterally for this purpose and it acts at the 105 right time when the frame 20 descends and the plunger is down.

What I claim is:

110 A soldering machine for dry batteries having a support for a battery can and a rest for the binding post, an axially rotatable flux supplying pipe, a vertically slideable frame and means therewith to rotate said pipe, a solder heating and applying plunger on said frame, a solder supply 115 mechanism actuated by said frame and a treadle to reciprocate the frame.

In testimony whereof I affix my signature in presence of two witnesses.

PHILIP P. NUNGESSION.
